UNITED STATES PATENT OFFICE.

RICHARD E. KRAUSE, OF CLEVELAND, OHIO.

CARBURETER.

1,124,918.

Specification of Letters Patent.

Patented Jan. 12, 1915.

Application filed April 18, 1911. Serial No. 621,784.

To all whom it may concern:

Be it known that I, RICHARD E. KRAUSE, a subject of the King of Sweden, resident of Cleveland, county of Cuyahoga, and State of Ohio, have invented a new and useful Improvement in Carbureters, of which the following is a specification, the principle of the invention being herein explained and the best mode in which I have contemplated 10 applying that principle, so as to distinguish it from other inventions.

This invention relates to a carbureter, and more particularly to one in which there is an automatic control of the richness of the 15 explosive mixture through the employment of a single jet construction. As is well-known, it is necessary that the explosive mixture be of a certain predetermined character as regards the proportion of fuel and 20 air, also that this character is determined by the relation of the area of the discharge opening of the fuel nozzle to the area of air inlet surrounding such nozzle.

The special object of this particular invention is to attain an automatic control of 25 the character of the explosive mixture in a more economical and efficient manner.

The said invention consists of means 30 which are hereinafter fully described and particularly pointed out in the claims.

The annexed drawings and the following description set forth in detail certain means embodying my invention, the disclosed means, however, constituting but one of 35 various mechanical forms in which the principle of my invention may be applied.

In said annexed drawings: Figure 1 is an elevation of a carbureter embodying my invention. Fig. 2 is a vertical section of the 40 same. Fig. 3 is a section on line III—III of Fig. 2, looking in the direction of the arrows. Fig. 4 is a detail view on line IV—IV of Fig. 1, looking in the direction of the arrows.

45 The carbureter constructed in exemplifying accord with the present conception comprises a main casing A forming two separated chambers A' and a'. The latter constitutes a reservoir for the hydro-carbon 50 fuel, which is supplied through the pipe a² and needle valve a³, this latter being controlled in the usual manner by means of a float a⁴ and actuating lever a⁵ connected thereto. An outlet a⁶ is provided as shown, 55 to which a bent conducting pipe a⁷ is con-

nected. The other chamber A' comprises the carbureting chamber proper, and is in fact the portion of the carbureter as a whole with which this invention is concerned. The chamber A' is open above and below, and 60 interiorly is fashioned with a plurality of upright diametrically disposed guides A² having overhanging upper portions A³ for a purpose soon to become apparent. These guides A² prescribe a substantially cylindrical compartment A⁴ most clearly appearing 65 in Fig. 2.

A nozzle-supporting member B is screwed into the lower open end of the chamber A', and is provided with a suitable connection 70 for the feed-pipe a². Any approved type of nozzle C is centrally mounted upon the member B and in its upright position is adapted to communicate with the feed-pipe through 75 said connection.

Superimposed within the cylindrical compartment A⁴ and loosely and gravitationally resting about the nozzle C and upon the upper surface of the member B, are a plurality 80 of rings D having downwardly projecting shoulders d' contiguous to their openings. These rings vary in thickness and therefore in weight, the heaviest being underneath 85 and provided with the largest opening, while the remainder are progressively lighter and provided with correspondingly smaller 90 openings in similar successive progression, so that the lighter will be uppermost. The upper ring as shown in the drawing is of lesser diameter than the others, and furthermore is provided with a downwardly extending boss, whereby it may be guided directly by the nozzle rather than by the 95 guides A², as in the case of the other rings. This upper ring, which is the lightest, is 100 purposely provided with an opening of very small area, for reasons to be presently explained. Its smaller diameter is nevertheless somewhat greater than the distance from each other of the diametrically opposite overhanging portions A³ of the guides A², whereby the extent to which it, and hence the remainder of the rings, may be 105 raised by the suction of the engine when in operation, is positively restricted. The upper open end of the chamber A' is in fact an upwardly projecting hollow boss A⁵. This constitutes the discharge outlet from 110 the carbureting chamber. It is controlled by the usual type of manually operable

throttle valve E, through the agency of which the opening may be increased or diminished, as is customary in the art.

The upwardly extending boss A⁵ is provided with two oppositely disposed bosses F, each of which is, in turn, provided with a laterally disposed flange f' having a screw-threaded opening f² adapted to receive a set-screw f³. The lever e' which 10 serves to operate the throttle-valve E is, in accordance with my invention, provided with a laterally extending lug e², adapted to engage in its upward movement this set-screw f³. The purpose of this is to make it 15 possible to definitely limit the extent to which the discharge outlet may be restricted by the valve E. It should be especially noted that the construction permits the set-screw to be placed on either side, and hence 20 the lever to be operated from either side, in accordance therewith. Furthermore, the lever may be placed on either side of the boss A⁵, in case the relative position of the carbureter with respect to the other engine 25 parts should so warrant.

During operation, it will be noted that when the cranking of the engine is commenced, only the relatively minute opening in the uppermost ring is afforded for the 30 upward passage of air. Consequently the air supply is substantially shut off during cranking, and prior to the starting, of the engine, and a correspondingly greater proportion of fuel necessarily drawn up 35 through the nozzle. This at that time serves the exact purpose of a primer, and in so doing constitutes an additional feature of my invention. Directly the engine has started and the suction in the carbureting chamber simultaneously increased, the opening in the uppermost ring will prove inadequate, and the latter will be raised against the action of gravity. Thereafter, when it is desired to increase the speed of the engine, and 40 the throttle-valve is opened still wider, a greater amount of fuel being thereby caused to flow up through the nozzle, the larger opening in the next lower ring with its correspondingly greater supply of air, is that 45 one which prescribes the amount of air properly proportionate to the amount of fuel rising through the nozzle. Any further opening of the throttle-valve will necessarily produce a similar result to the one 50 just described, so that one after the other of the several rings is raised against the action of gravity, beginning, as already stated with the lightest, which is uppermost, and has the smallest opening. This consequently 55 places the successive areas of the various air inlet openings of the several rings into a 60

controlling operation which is progressive, and consonantly the velocity of air is maintained substantially constant between predetermined limits. By increasing the number of rings, the frequency and hence the precision of the automatic adjustment may be correspondingly increased. The character of the explosive mixture supplied to the engine cylinders may accordingly be maintained at a point as nearly constant as may in practice be found feasible for economical efficiency.

Having fully described my invention, what I claim and desire to secure by Letters Patent is:—

1. A carbureter comprising the combination of a casing forming a carbureting chamber having an air-inlet below and a valve-controlled outlet above for the carbureted air; a fuel nozzle projecting into said air-inlet and discharging into said chamber, and a plurality of superimposed rings of same diameter, surrounding said fuel nozzle having shoulders and openings of different size contiguous thereto, said openings surrounding said nozzle, for progressively varying the area of said air-inlet directly as the variation of pressure at said outlet, whereby the velocity of the air is maintained between predetermined limits; the said inlet forming the sole means of entrance of air into said chamber.

2. A carbureter comprising a carbureting chamber provided with a fuel nozzle and an air inlet, and an outlet for the carbureted air, said chamber being further provided interiorly with a plurality of diametrically disposed upright guides, and a plurality of superimposed rings of same diameter, surrounding the fuel nozzle having openings of different size, for varying the area of said air-inlet, and movable between said guides.

3. In a carbureter comprising a casing having an air chamber provided with an air inlet and an outlet, the combination of a fuel supply member extending upward in the axis of said inlet into said chamber, a valve slideable upon said supply member to control the air inlet, a plurality of concentric tubular gravity members surrounding the supply member and valve, and means within the chamber for guiding said tubular members and supporting the same at different heights.

Signed by me, this 10th day of April, 1911.

RICHARD E. KRAUSE.
